COFFEE POT OR ARTICLE OF ANALOGOUS NATURE

Filed July 7, 1931

Inventor:

Harold E. Nock
by Norman G. Ogden
his Attorney

UNITED STATES PATENT OFFICE

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS

DESIGN FOR A COFFEE POT OR ARTICLE OF ANALOGOUS NATURE

Application filed July 7, 1931. Serial No. 40,451. Term of patent 14 years.

To all whom it may concern:

Be it known that I, HAROLD E. NOCK, a citizen of the United States and a resident of Newburyport, in the county of Essex and Commonwealth of Massachusetts, have invented a new, original, and ornamental Design for a Coffee Pot or Article of Analogous Nature, of which the following is a specification, reference being had to the accompanying drawing, forming a part thereof.

In the accompanying drawing the Figure is a view, in side elevation, of a coffee pot showing my new design.

The design is delineated as embodied in a coffee pot but it is contemplated that the design may also be embodied in or applied to a tea pot, sugar or waste bowl, cream or water pitcher, gravy boat or other analogous piece which may form part of a hollow-ware service of a uniform pattern.

I claim:

The ornamental design for a coffee pot or article of analogous nature, substantially as shown and described.

HAROLD E. NOCK.
